VALVE SEAT GRINDER

John W. Holland, Fitchburg, Mass., assignor to Holland-Kenyon Machine Company, Fitchburg, Mass., a partnership consisting of John W. Holland and Samuel A. Kenyon

Application May 4, 1934, Serial No. 723,947

9 Claims. (CL 51—241)

The present invention relates to a portable tool for the grinding of valve seats in internal combustion engines, the tool being particularly useful in the grinding of the hardened valve seat inserts found in certain of the present day automobile engines.

In prior devices of this character, the grinding wheel is centered with respect to the valve seat by a pilot engageable with the valve guide. In this type of grinder, the wheel engages simultaneously with all portions of the valve seat and, in the grinding of valve seats in this manner, the wheel rapidly becomes gummed, requiring frequent dressing operations on said wheel in order to maintain a suitable cutting surface.

The objections to the concentric grinding of valve seats have been eliminated in eccentric valve seat grinder constructions in which the axis of rotation of the cutting wheel is eccentric to the pilot on which the device is mounted, the wheel being turned about the pilot for engagement successively with all points on the valve seat. The present invention involves, in this type of grinder, the provision of means for adjusting the grinding member axially toward and away from the valve seat; this adjustment being procured by means of a member engageable with a portion of the engine, thus supporting the grinding member against axial movement relative to the valve seat for producing a perfectly true valve seat.

Portable valve seat grinders, of either the eccentric or concentric type are, in general, supported entirely upon the pilot, and if the grinder is not balanced about the axis of the pilot, the latter, being relatively slender, is sprung by the weight of the device and produces an uneven valve seat. A further object of the present invention is to avoid any tendency of the device to spring the pilot by providing a device which is substantially balanced about the axis of the pilot. At the same time, the present device is constructed so that its weight is supported upon a portion of the engine in which the valve seat is located rather than being supported by a pilot.

The usual type of pilot for locating the grinder relative to the valve seat has a tapered lower end which engages the valve guide adjacent the valve seat. Since the several valve guides in an engine do not wear uniformly, the upper or centering portion of the pilot does not assume the same position relative to the valve seat when positioned in successive valve guides. Accordingly, for each valve seat, a grinder which is supported entirely by the pilot must be adjusted to compensate for the varying positions of said pilot. This extensive adjustment is overcome by the present invention since the device is supported on a portion of the engine which is in predetermined relation to the corresponding valve seat.

Other and further objects and advantages of

the invention will appear from the following detailed description taken in connection with the accompanying drawing in which:—

Fig. 1 is a front elevation of a device embodying the invention.

Fig. 2 is a vertical sectional view through the device, showing the latter in position on a pilot, and showing the relation of the device to a valve seat.

Fig. 3 is an enlarged detail of a portion of the device, showing the driving means for the grinding wheel.

Fig. 4 is a fragmentary sectional view along the line 4—4 of Fig. 1, showing the valve for controlling the supply of fluid to the device.

Like reference characters refer to like parts in the different figures.

The device, which is intended to be driven by air under compression, such air being available in all garages which are provided with compressed air tanks for the inflation of pneumatic tires, is arranged to be positioned on a pilot which locates the device in eccentric relation to the valve seat. The device is shown in connection with an automobile engine block in which the valve seat to be ground is located. Said valve seat may be formed in the engine block or in a hardened insert positioned in said block.

Referring first to Fig. 2, the engine block 1 from which the cylinder head has been removed, has a valve seat 2 which, in the construction shown, is formed in a hardened steel ring 2a permanently secured in the engine block. Beneath the valve seat 2 is located a bore 3 concentric to the valve seat, said bore receiving the usual valve guide 4 having the usual axial bore in which the valve stem of the valve, not shown, is slidable. The valve guide 4 fits tightly in the bore 3 and forms a part of the engine block, the upper surface of said guide being in substantially predetermined relation to the valve seat. For supporting the device of the present invention in predetermined relation radially of the valve seat during the grinding of said seat, the valve guide receives a pilot 5 which is of any suitable well-known construction, said pilot having an upper cylindrical portion 6 and the lower portion 7 of said pilot being tapered to fit tightly in the guide 4 as the pilot is pushed downwardly therein. The tapered portion 7 provides for accurate centering of the pilot relative to the valve seat, the portion 6 of the pilot extending beyond and above the valve seat in concentric relation thereto.

The device of the present invention is mounted on the pilot and is adapted to be rotated thereon for grinding of the entire surface of the valve seat. Referring again to Fig. 2, the device comprises an inner rod 8 having an axial bore 9 in the lower end thereof, said bore forming the lower part of the rod into an eccentric sleeve 10

whose extreme lower end engages the upper end of the valve guide 4 as indicated, thus supporting the weight of the entire device on the cylinder block. The upper end of the rod 8 is threaded on its outer surface for a purpose which will hereinafter appear.

Secured against turning movement on said sleeve, but axially slidably thereon, is a hollow shaft 11 having a concentric bore, said shaft 10 carrying a pin 12 engageable in an axial slot 13 in the rod 8 for preventing relative turning movement between said sleeve and shaft. Said shaft 11 has an annular flange 14 thereon against whose under side are positioned in spaced relation the inner races of ball bearings 15, said races being spaced apart by a ring 16 and being clamped against movement on said shaft 11 by threaded rings 17 engaging a threaded portion of said shaft. The outer ring of the upper ball bearing 15 is slidably in a cylindrical bore 18 of a sleeve 19, and the outer race of the lower ball bearing 15 is clamped against movement in said sleeve by an annular member 20 which has an externally threaded portion at the upper end thereof engageable with an internally threaded portion of the sleeve 19. A screw 21 extending through said sleeve and member prevents relative rotation thereof and also provides for the admission of oil for the ball bearings, the latter supporting both the sleeve and member rotatably on the shaft 11. The lower end of the annular member 25 has a concentric bore 22 through which the sleeve 10 extends, and a reduced externally threaded portion of said member receives and supports the grinding wheel 23, the latter being internally threaded for engagement therewith. Said wheel, as will be apparent, has a tapered conical surface 24 which corresponds to the desired taper of the valve seat.

40 The shaft 11 has a member 25 journaled thereon above the flange 14 and said member is held against axial sliding movement on said shaft by an arm 26 which is secured against turning movement on said shaft at the upper end thereof by a clamping screw 27 extending through lugs 28 on opposite sides of a radial slot 29 in said arm. The member 25 has secured thereto a shell 30 which has a depending cylindrical flange 31 extending downwardly over the sleeve 19. The member 25 has a radial flange 32 at the lower end thereof which engages with the cylindrical flange 31 on the shell to define an annular air space 33 between said member and shell.

Air from any suitable source is supplied to this air space 33 through the structure indicated in Fig. 4. Referring to this figure, the shell has a bore 34 therein which receives a plug 35 in which an air valve is positioned. Said valve comprises a ball 36 which engages with a tapering seat 37 provided in said plug, said ball being held against said seat by a coil spring 38 which engages with said ball at the other end and with a recess 39 in a connecting member 40 threaded into said plug. Said connecting member has a channel extending therethrough and the outer end of said member is arranged to be connected to a suitable air hose 41 for connecting said member to the air supply. The plug has an axial channel 42 extending inwardly from the valve seat and the bore 34 in the shell which receives said plug is connected by a channel 43, Fig. 3, to the annular air space 33 above referred to. A pin 44, which is axially slidable in a small bore 45 in the shell 75 has an outwardly extending head 46 on one end

thereof and engages at the opposite end with the ball 36 which controls the air supply. Pressure on the head 46 withdraws the ball from the valve seat and allows air under pressure to enter the annular air space 33 for actuating the device.

Referring now to Fig. 3, the flange 32 on the lower end of the member 25 has spaced arcuate grooves 47 therein to provide for the passage of air from the air space 33 downwardly past said flange and against blades 48 provided on the surface of the sleeve 19, these blades being formed by cutting slots in said member, as indicated. A ring 49, which is received in a groove 50 in the outer surface of the sleeve 19, is secured against turning movement relative to the shell by screws 51 extending through said shell, and said ring is provided on its outer surface with arcuate slots 52 which provide blades for directing the air from the moving blades 48, above referred to, to a second set of blades 53 also provided on the outer surface of the sleeve 19, in spaced relation to the blades 48. The arrangement above described constitutes a two-stage turbine for driving the grinding wheel, the air from the second set of blades on the sleeve 19 escaping beyond the bottom of the shell.

The arm 26, which, as above stated, is secured against turning movement on the upper end of the shaft 11, has a handle 54 by which said shaft, as well as the eccentric sleeve 10 may be turned about the axis of the pilot, thereby turning the grinding wheel about the pilot to carry the cutting surface of said wheel over the entire surface of the valve seat. Said arm 26 has upwardly projecting lugs 55 which support a plate 56 in spaced relation to said arm, and a nut 57 having a knurled outer surface is supported between said plate and the arm, being held resiliently against turning movement by spring-pressed plungers 58 slidable in small bores in the arm. The nut 57 has a depending cylindrical sleeve 59 which is internally threaded for engagement with the threads on the upper end of the rod 8. Rotation of the nut relative to the arm will provide for a vertical movement of the rod 8 relative to the remainder of the device to provide for vertical adjustment of the grinding wheel toward or away from the valve seat.

In operation, the device is mounted on the pilot in the position shown in Fig. 2, with the pilot positioned in the bore 9, and with the lower end of the sleeve 10 engaging with the engine, and the knurled nut 57 is then turned until the grinding wheel engages with the valve seat at one point thereof. The operator then opens the air valve by pressure on the head 46 and turns the handle to rotate the grinding wheel about the axis of the pilot. Since the shell is held stationary, the sleeve 19 and the grinding wheel supported thereby is rotated at a rapid rate by the air under compression and procures a grinding operation on the valve seat. Said wheel, by reason of the eccentric sleeve 10 is eccentric to the axis of the pilot and engages, at one time, with only one portion of the valve seat. As the handle is turned, however, the grinding wheel is carried about the axis of the pilot and grinds all portions of the valve seat. Since the rod 8 supports the device against vertical movement, the wheel grinds the seat to the perfect conical form desired, and since the device is substantially balanced about the axis 150

of the pilot, the weight of the device cannot spring the pilot to produce an untrue seat. Since the device is supported on the upper end of the valve guide which is in predetermined relation 5 to the valve seat, it will be clear that the successive valve seats of an engine may be ground without any extensive adjustment of the device relative to the seats; the only adjustment necessary is the slight axial adjustment to compensate for the varying wear on the several seats.

I claim,

1. A grinder for the valve seats of engines, the latter having, during the grinding of each seat, a pilot for locating the grinder in predetermined 15 relation radially of said seat, said grinder comprising a shell, a grinding wheel, a member journaled within said shell and supporting said wheel, means including an eccentric sleeve adapted to extend over the pilot for positioning the wheel 20 in eccentric relation to the valve seat, said sleeve extending axially through said shell and member, said sleeve being adjustable axially within the shell and engageable with a portion of the engine in predetermined relation to the valve seat for 25 adjusting the position of the grinding wheel axially of said seat.

2. A grinder for the valve seats of engines, the latter having, during the grinding of each seat, a pilot for locating the grinder in predetermined 30 relation radially of said seat, said grinder comprising a shell, a grinding wheel, a member journaled within said shell and supporting said wheel, means including an eccentric sleeve adapted to extend over the pilot for positioning the 35 wheel in eccentric relation to the valve seat, said sleeve extending axially through said shell and member and being turnable within said shell, said sleeve being adjustable axially within said shell and extending beyond the wheel for engagement 40 with a portion of the engine to support the wheel in predetermined axial relation to the valve seat.

3. A grinder for the valve seats of engines, the latter having, during the grinding of each seat, a pilot for locating the grinder in predetermined 45 relation radially of said seat, said grinder comprising a shell, a grinding wheel, a member journaled within said shell and supporting said wheel, means including an eccentric sleeve adapted to extend over the pilot for positioning the wheel 50 in eccentric relation to the valve seat, said sleeve extending axially through said shell and member and being turnable within said shell and member, said sleeve extending beyond the wheel for engagement with a portion of the engine to support 55 the wheel in predetermined axial relation to the valve seat, and means for adjusting the grinding wheel and shell axially of said sleeve.

4. A grinder for the valve seats of engines, the latter, during the grinding of each seat, having 60 a pilot positioned therein for locating the grinder in predetermined radial relation to the seat, said grinder comprising a shell, a grinding wheel, a sleeve journaled within said shell and extending therefrom for supporting the grinding wheel, means for procuring a rotation of said sleeve 65 within said shell for a rotation of the grinding wheel, a second sleeve extending through said shell and first sleeve and engageable over the pilot for locating the grinding wheel relative to the 70 valve seat, said second sleeve extending beyond the grinding wheel for engagement with a portion of the engine in predetermined relation to the valve seat, and means for shifting said second sleeve axially within said shell.

5. A grinder for the valve seats of engines, the

latter, during the grinding of each seat, having a pilot positioned therein for locating the grinder in predetermined radial relation to the seat, said grinder comprising a shell, a grinding wheel, a sleeve journaled within said shell and extending therefrom for supporting a grinding wheel, means for rotating said sleeve within said shell, a second sleeve extending through said shell and said first sleeve and engageable with the pilot for locating the grinding wheel in predetermined relation to the seat, said second sleeve extending beyond the grinding wheel for engagement with a portion of the engine in predetermined relation to the valve seat for supporting said wheel in predetermined axial position relative to said seat, said sleeves being freely turnable relative to each other without any corresponding axial movement, and means for shifting said second sleeve axially relative to the shell and said first sleeve.

6. A grinder for the valve seats of engines, the latter, during the grinding of each seat, having a pilot for locating the grinder in predetermined position radially of said seat, said grinder comprising a shell, a sleeve journaled within said shell, a grinding wheel secured to said sleeve, an eccentric sleeve extending axially through said shell and said first sleeve for engagement with the pilot, said eccentric sleeve being turnable within said shell and said first sleeve and being axially adjustable within said shell, and a handle 105 secured to said eccentric sleeve for a rotation of said sleeve within said shell and said first sleeve.

7. A grinder for the valve seats of engines, the latter, during the grinding of each seat, having a pilot positioned in concentric relation to said seat, 110 said grinder comprising a shell, a sleeve journaled within said shell, a grinding wheel on said sleeve, means engageable with the pilot for locating said sleeve and shell in predetermined relation to the valve seat, said sleeve and shell having cooperat- 115 ing vanes forming a fluid motor for a positive rotation of the sleeve within said shell.

8. A grinder for the valve seats of engines, the latter, during the grinding of each seat, having a pilot positioned in concentric relation to said seat, 120 said grinder comprising a shell, a sleeve journaled within said shell, a grinding wheel on said sleeve, means engageable with the pilot for locating said sleeve and shell in predetermined relation to the valve seat, said sleeve and shell having 125 cooperating vanes forming a fluid motor for a positive rotation of the sleeve within said shell, and a valve positioned in said shell for controlling the admission of fluid to said fluid motor.

9. A grinder for the valve seats of engines, the latter, during the grinding of each seat, having a pilot for locating the grinder in predetermined relation radially of said seat, said grinder comprising a substantially cylindrical shell, a sleeve journaled within said shell on an axis substan- 135 tially concentric with the axis of said shell, a grinding wheel on said sleeve, an eccentric sleeve journaled within said shell and turnable within said first sleeve, the outer surface of said eccentric sleeve being substantially concentric to the 140 axis of said first sleeve and said shell, means for adjusting said eccentric sleeve axially relative to said shell and first sleeve, and a fluid pressure motor for procuring a rotation of said first sleeve within the shell, said motor comprising cooperat- 145 ing vanes on the adjacent surfaces of said sleeve and shell, and a valve in said shell for admitting fluid under pressure to said vanes.
